UNITED STATES PATENT OFFICE.

RAYMOND B. GILCHRIST, OF NEWARK, NEW JERSEY, ASSIGNOR TO THE GILCHRIST COMPANY, OF NEWARK, NEW JERSEY, A CORPORATION OF NEW JERSEY.

DRINK MIXER.

Application filed March 8, 1922. Serial No. 541,909.

To all whom it may concern:

Be it known that I, RAYMOND B. GILCHRIST, a citizen of the United States, and a resident of Newark, in the county of Essex and State of New Jersey, have invented certain new and useful Improvements in Drink Mixers, of which the following is a full, clear, and exact description.

The invention relates to drink mixers.

10 In machines for this purpose, the liquid constituents of the drink to be mixed are usually poured into a receptacle which is generally designated a "shaker," from many different containers disposed away from the mixer. The receptacle with these constituents therein is brought to the mixer and placed in operative relation thereto and is removed from the machine after each mixing operation, to discharge its contents. This is rendered necessary, because so many different ingredients and flavors are used in making drinks that they are, in nearly all cases, mixed individually. It is usually necessary to run the 20 agitator for a considerable period to properly blend or mix the constituents and, therefore, it is desirable that provision be made for retaining the receptacle and agitator in operative relation to permit the dispenser 25 to perform other duties during the mixing operation. In drink mixing, it thus becomes necessary to frequently place the receptacle containing the constituents into cooperative relation to the agitator and to withdraw it 30 from the machine to discharge its contents and cleanse the receptacle between mixing operations.

A desideratum in this art is to expedite and simplify the operations necessary to bring the receptacle and agitator into cooperative relation, to maintain them in such relation, in starting and stopping of the motor and the removal of the receptacle. Heretofore, in machines whereof I am aware (excluding those exhibited in concurrently pending applications), it has been necessary in their use to manually manipulate the receptacle into operative position and withdraw it therefrom and to additionally perform some separate step or operation, such as lowering the motor and agitator together, or shifting the agitator and its shaft into the receptacle and relatively to the motor, or raising and locking a receptacle-support to establish and maintain cooperative relation

of the receptacle and agitator or to control the operation of the machine. Another desideratum in this art is to simplify the machine by dispensing with movable connections in and for the driving mechanism for the agitator.

One object of the present invention is to provide an improved drink mixer in which these additional operations or steps are dispensed with and in which manual shift of the receptacle is utilized to completely control the operation of the machine and to secure it and the agitator in cooperative relation. By dispensing with the necessity of these additional steps or operations, the time of the dispenser in performing them is saved and the service is improved.

Another object of the invention is to provide a machine which is simple in construction, which may be easily and readily operated and which is efficient in operation.

Another object of the invention is to provide a machine of this type in which movable connections in and for the driving mechanism for the agitator are dispensed with.

Other objects of the invention will more fully appear from the following description.

The invention consists in the several novel features hereinafter set forth and more particularly defined by claims at the conclusion hereof.

In the drawings: Fig. 1 is a vertical section of a machine embodying the invention. Fig. 2 is a front view, the motor and agitator being removed. Fig. 3 is a section on line 3—3 of Fig. 1. Fig. 4 is a similar view to Fig. 1 showing the machine idle. Fig. 5 is a similar view to Fig. 4 showing the receptacle tilted to unlock it for withdrawal. Fig. 6 is a detail section on line 6—6 of Fig. 2. Fig. 7 is a detail of a portion of the supporting standard.

The invention is exemplified in a machine comprising an electric motor 8 which is supported at the upper end of a standard 9 which serves as a stationary support for the motor. Its lower end is rigid with a base 10 which is usually adapted to rest on a counter or table. A shaft 11 secured to the rotor of the motor projects downwardly from the motor case and is provided at its lower end with a suitable agitator 12 for mixing the constituents of a drink, as

well understood in the art. Shaft 11 is of sufficient length so that the agitator will reach the constituents of a drink to be mixed near the bottom of an open topped receptacle 19 held below the motor and containing said constituents. There is sufficient clearance below the agitator to permit the receptacle 19 to be placed beneath and around the agitator without spilling its contents and without the necessity of lowering the agitator into the receptacle. In the present invention, the relationship between the agitator and the motor or between the agitator and the base are not varied and 15 the receptacle only is manipulated in establishing cooperative relationship between the receptacle and the agitator, so that movement of the agitator or the agitator and motor are not necessary for this purpose.

20 The case of the motor 8 is rigidly secured by screws 13 to lugs 14 which are integral with the upper end of the standard. A case 15, containing an electrical switch of usual construction and having its members 25 connected to control the motor 8, is firmly secured to the outside of the motor-casing. A spring-pressed button 15^b operates the switch in the case 15 to close the circuit for causing the motor 8 to run when and while 30 the button is pushed upwardly and to open said circuit to stop the motor when the button is released. The switch-members in the case 15 may be of standard construction, as well understood in the art, so that 35 detailed illustration has not been deemed necessary. Yielding contact-strips 16^a, adapted to enter a switch-socket of usual construction, project rearwardly from the case 15, so that the necessary electrical connections to supply current to the motor will 40 be made by pushing an ordinary conductor socket, which is adapted to receive said contact-strips and is connected by a flexible cord-conductor to a suitable source of energy, into connected relation with said strips.

The inner face of the standard 9 has an arcuate front face 18, to form a vertical guide for receptacle 19 which is adapted 50 to be placed against the arcuate face 18 beneath the agitator 12, said face and receptacle being conformably curved so the receptacle, while pressed against said face, will be held against lateral movement. This 55 construction provides for guiding the receptacle, while manually supported, into operative position around the agitator. The arcuate face or guide 18 extends vertically to guide the receptacle 19 until it 60 has been elevated sufficiently to establish cooperative relation between the agitator and the contents of the receptacle. The operator, in lifting the receptacle, exerts backward pressure against the receptacle, so it will be definitely controlled in its

movement around the agitator and will not strike it. The receptacle 19 is provided with an upper reinforcement or wear-band 21, and a lower band 21^a. In drink mixers of this type, it is generally necessary that the 70 mixing operation must continue for a considerable period and that provision be made for retaining the receptacle in operative position without aid of the operator after it has been placed in such position. For 75 this purpose, a ledge or shoulder 27 is formed on the standard 9 at a point where it will underlie and form a rest for the shoulder formed by the lower end 23 of band 21. These shoulders, when one is 80 superposed on the other, constitute an interfitting connection directly between the receptacle and the stationary supporting standard, whereby the receptacle will be positioned and supported for an agitating 85 operation. A holder 24 is pivotally supported by a pin 25 which is suitably held in standard 9 and comprises an arm or member 26 which is adapted to engage the inner periphery of the receptacle 19 adjacent the 90 upper rim and press it backwardly, so that the shoulder 23 will be held on the shoulder 27 and thus cause the receptacle to be locked in its operative position. A spring 27' is applied to the holder 24 to normally press 95 member 26 backwardly to yieldingly hold the receptacle on the supporting-shoulder 27. A stop lug 28 is provided on the holder to engage the rear of the supporting standard and limit the rearward movement of the 100 gripping member 26. The lower end of member 26 is curved forwardly, as at 29, to deflect the receptacle as it is manually supported and being raised into the space between said member and the guide 18. Spring 27' also permits the holder member 26 to be swung forwardly by the receptacle a sufficient distance to permit band 21 to pass between it and the guide 18 and above shoulder 27, as the receptacle is being raised 105 into its operative relation around the agitator and to be swung forwardly sufficiently to permit the shoulder 23 on the receptacle to be disengaged from the shoulder 27 after an agitating operation and in the removal 115 of the receptacle. A stop 30 is provided on the holder 24 to engage the front of the standard 9 and prevent excessive movement of the holder-member 26, so that the receptacle cannot be tilted forwardly sufficiently to strike the agitator in releasing it and withdrawing it from the holder.

A lever 32 has its lower end pivoted, at 33, in the standard 9, and is provided with an upper cam terminal 34 which is adapted to shift switch-button 15^b upwardly into position to close the switch for controlling the motor 8. This lever is yieldingly held and pressed into position to release the button 15^b by a spring 35, a stop 36 being provided 125

to normally position this lever. The latter is provided with a cam or projecting portion 37 which projects through a slot 38, which is formed in the standard 9, and into 5 the path of the receptacle 19 as it is being raised into and lowered from its operative position and is being guided by the arcuate guide-face 18. As a result, receptacle 19, as it is being thus raised, will engage the 10 lever 32 and swing it backwardly against the force of spring 35 and shift its upper end 34 to push the button 15^b upwardly to close the switch in the case 15 and automatically start the motor 8. The upper end 15 of the cam 37 is disposed where it will be held in position by the upper portion of the receptacle 19, to cause the lever 32 to retain the switch closed while the receptacle is locked in its operative position. The 20 force of the spring 27' is sufficient to hold receptacle 19 and lever 32 against the force of the spring 35 which requires only sufficient force to move the lever 32.

The operation will be as follows: When 25 the machine is idle, the holder 27 and switch-lever 32 will be in position shown in Fig. 5. The operator will place a receptacle 19, containing the constituents of the drink to be mixed, against the lower portion of guide 30 18 under the agitator 12 and then manually raise the receptacle pressing it manually against said guide to confine it against lateral movement. As the upper margin of the receptacle encounters the lower end of the 35 cam 37 of the switch-lever 32, it will swing said lever backwardly and cause its upper end 34 to force the button 15^b upwardly and into position to close the switch in case 15 and start the motor 8. As the upper end 40 of the receptacle, encounters the lower end of the holder-member 26, it will force it forwardly against the force of spring 27, sufficiently to permit the wear-band to pass above the supporting shoulder 22, as shown 45 in Fig. 1 and then the force of said spring will press the receptacle backwardly to bring the shoulder 23 on the receptacle over the stationary shoulder 22 and cause the receptacle to be locked in operative position, then, the operator will release the receptacle and it will remain locked in operative 50 position. The switch lever 32 will be retained in position to close the motor switch as long as the receptacle remains in such 55 position. When the mixing operation has been completed, the operator will grasp the lower portion of the receptacle and swing it forward slightly to cause the shoulders on the receptacle and the standard to be disengaged or clear one another, as shown by dotted lines in Fig. 1 and, thereupon, the receptacle will be unlocked so it can be lowered below the agitator and withdrawn 60 from guide-face 18. During this tilting, stop 30 becomes active to prevent excessive 65

forward movement of the lower end of the receptacle which might cause it to strike the rotating agitator. When the receptacle has been lowered sufficiently to release the cam 37, spring 35 will restore the switch-lever 32 and cause the spring-pressed button 15^b to be lowered sufficiently to open the motor-switch and cause the motor to stop. 70

The invention exemplifies a drink-mixer in which the motor and agitator are maintained in fixed relation and in which placement of the receptacle in operative position causes it to be automatically secured in position for operation; in which the receptacle is supported and locked in operative position entirely by means adjacent its upper end, so that no lower support or shelf is necessary; in which a spring-pressed member locks the receptacle in operative position; in which placement and removal of the receptacle cause the receptacle to be automatically locked and released and automatically control the motor switch and in which the receptacle is guided into and out of operative position. 75 80 85 90 95

The invention is not to be understood as restricted to the details set forth, since these may be modified within the scope of the appended claims, without departing from the spirit and scope of the invention. 95

Having thus described the invention, what I claim as new and desire to secure by Letters Patent, is:

1. In a machine of the character described, the combination of a motor, an agitator driven thereby and supported from above with sufficient clearance to permit a receptacle with an open top to be placed into operative position around the agitator, and means to grip the upper portion of the receptacle to secure it in operative position. 100 105

2. In a machine of the character described, the combination of a motor, an agitator driven thereby and supported from above with sufficient clearance to permit a receptacle with an open top to be placed into operative position around the agitator, means to grip the upper portion of the receptacle to secure it in operative position, and means to guide the receptacle while it is manually supported, to said gripping means. 110 115

3. In a machine of the character described, the combination of a motor, an agitator driven thereby and supported from above with sufficient clearance to permit a receptacle with an open top to be placed into operative position around the agitator, and means to grip the upper portion of the receptacle to hold it in operative position comprising a spring-pressed member and a stationary member. 120 125

4. In a machine of the character described, the combination of a motor, an agitator driven thereby and supported from above 130

with sufficient clearance to permit a receptacle with an open top to be placed into operative position around the agitator, means to grip the upper portion of the receptacle to hold it in operative position, comprising a spring-pressed member and a stationary member, and means to guide a manually supporting receptacle to said gripping means.

10. 5. In a machine of the character described, the combination of a motor, an agitator driven thereby and supported from above, with sufficient clearance to permit a receptacle with an open top to be placed into operative position around the agitator, and means to lock the receptacle in operative position comprising members to engage the inner and outer sides of the upper portion of the receptacle, one of said members being 20 spring-pressed.

6. In a machine of the character described, the combination of a motor, an agitator driven thereby and supported from above with sufficient clearance to permit a receptacle with an open top to be placed into operative position around the agitator, means to rock the receptacle in operative position comprising members to engage the inner and outer sides of the upper portion of the receptacle, one of said members being spring-pressed, and means to guide the receptacle while manually supported to said locking means.

7. In a machine of the character described, 35 the combination of a motor, an agitator driven thereby and supported from above with sufficient clearance to permit a receptacle with an open top to be placed into operative position around the agitator, 40 means to automatically lock the receptacle in operative position comprising a spring-pressed holding member releasable by manipulation of the receptacle itself, and means for automatically controlling the motor operable by manual placement of the receptacle itself into its operative position.

8. In a machine of the character described, the combination of a motor, an agitator driven thereby and supported from above 50 with sufficient clearance to permit a receptacle with an open top to be placed into operative position around the agitator, and means to automatically lock the receptacle in operative position, means to guide the receptacle to such position while manually supported, said locking means comprising a spring-pressed holding member for the upper margin of the receptacle, said member being releasable for withdrawal of the receptacle by manipulation of the receptacle itself.

9. In a machine of the character described, the combination of a motor, an agitator driven thereby and supported from above 65 with sufficient clearance to permit a recep-

tacle with an open top to be placed into operative position around the agitator, and means to automatically lock the receptacle in operative position when it has been manually shifted to such position, comprising a 70 spring-pressed member engaging the inner periphery of the upper portion of the receptacle.

10. In a machine of the character described, 75 the combination of a motor, an agitator driven thereby and supported from above with sufficient clearance to permit a receptacle with an open top to be placed into operative position around the agitator, and means to automatically lock the receptacle 80 in operative position when it has been manually shifted in such position comprising a spring-pressed member engaging the inner periphery of the upper portion of the receptacle, 85 said member being releasable by manipulation of the receptacle to permit its withdrawal from its locked position.

11. In a machine of the character described, 90 the combination of a support, a motor, an agitator driven by the motor and supported from above with sufficient clearance to permit a receptacle with an open top to be placed into operative position around the agitator, and means to secure the receptacle in operative position comprising an interfitting connection between the side of the receptacle and the support whereby the receptacle will be vertically secured.

12. In a machine of the character described, 95 the combination of a supporting standard, a motor mounted on said standard, an agitator driven by the motor and supported from above with sufficient clearance to permit a receptacle with an open top to be placed into operative position around the agitator, and means to secure the receptacle in operative position comprising an interfitting connection between the side of the receptacle and the standard whereby the receptacle will be vertically secured.

13. In a machine of the character described, 110 the combination of a support, a motor, an agitator driven by the motor and supported from above with sufficient clearance to permit a receptacle with an open top to be placed into operative position around the agitator, and means to secure the receptacle in operative position comprising shoulders on the side of the receptacle 115 and the support.

14. In a machine of the character described, 120 the combination of a support, a motor, an agitator driven by the motor and supported from above with sufficient clearance to permit a receptacle with an open top to be placed into operative position around the agitator, means to secure the receptacle in operative position comprising an interfitting connection between the side 125 of the receptacle and the support, and means 130

to guide the receptacle while it is manually shifted to said securing-means.

15. In a machine of the character described, the combination of a support, a motor, an agitator driven by the motor and supported from above with sufficient clearance to permit a receptacle with an open top to be placed into operative position around the agitator, means to secure the receptacle in operative position comprising an interfitting connection between the side of the receptacle and the support, and means on the support to slidably guide the receptacle while it is manually shifted to said securing means.

16. In a machine of the character described, the combination of a stationary support, a motor mounted at the upper end of the support, an agitator driven by the motor and supported from above with sufficient clearance to permit a receptacle with an open top to be placed into operative position around the agitator, means to secure the receptacle in operative position comprising an interfitting connection between the side of the receptacle and the support and a guide on the support to direct the receptacle while it is manually shifted to said securing means.

17. In a machine of the character described, the combination of a support, a motor, an agitator driven by the motor and supported from above with sufficient clearance to permit a receptacle with an open top to be placed into operative position around the agitator, and means to secure the receptacle in operative position comprising an interfitting connection between the side of the receptacle and the support, and means to press the receptacle and support together.

18. In a machine of the character described, the combination of a support, a motor, an agitator driven by the motor and supported from above with sufficient clearance to permit a receptacle with an open top to be placed into operative position around the agitator, and means to secure the receptacle in operative position comprising an interfitting connection between the side of the receptacle and the support, and a spring-pressed member engaging the inside of the receptacle.

19. In a machine of the character described, the combination of a support, a motor, an agitator driven by the motor and supported from above with sufficient clearance to permit a receptacle with an open top to be placed into operative position around the agitator, and means to secure the receptacle in operative position comprising interfitting shoulders between the side of the receptacle and the support, and means to press the shoulders into cooperative relation.

20. In a machine of the character de-

scribed, the combination of a support, a motor, an agitator driven by the motor and supported from above with sufficient clearance to permit a receptacle with an open top to be placed into operative position around the agitator, means to secure the receptacle in operative position comprising an interfitting connection between the side of the receptacle and the support, and means operated by the side of the receptacle for controlling the operation of the motor.

21. In a machine of the character described, the combination of a support, a motor, an agitator driven by the motor and supported from above with sufficient clearance to permit a receptacle with an open top to be placed into operative position around the agitator, and means to secure the receptacle in operative position comprising an interfitting connection between the side of the receptacle and the support, and means to limit the movement of the receptacle relatively to the support in removing the receptacle.

22. In a machine of the character described, the combination of a support, a motor, an agitator driven by the motor and supported from above with sufficient clearance to permit a receptacle with an open top to be placed into operative position around the agitator, and means to secure the receptacle in operative position comprising an interlocking connection between the side of the receptacle and the support, and means to limit the pivotal movement of the receptacle in removing it.

23. In a machine of the character described, the combination of a motor, a standard to the upper end of which the motor is secured, an agitator driven by the motor and supported from above with sufficient clearance to permit a receptacle with an open top to be placed into operative position around the agitator, and means to secure the receptacle in operative position, comprising a spring-pressed member having a portion in the path of and operated by the receptacle while it is being manually shifted to said position.

24. In a machine of the character described, the combination of a motor, a standard to the upper end of which the motor is secured, an agitator driven by the motor and supported from above with sufficient clearance to permit a receptacle with an open top to be placed into operative position around the agitator, means to secure the receptacle in operative position comprising a spring-pressed member having a part in the path of and operated by the receptacle while it is being manually shifted to said position, and means to limit the movement of said member, to limit the movement of the receptacle.

25. In a machine of the character de-

scribed, the combination of a motor, a stand-
ard to the upper end of which the motor is
secured, an agitator driven by the motor
and supported from above with sufficient
5 clearance to permit a receptacle with an
open top to be placed into operative posi-
tion around the agitator, means to secure
the receptacle in operative position, com-
prising a pivoted spring-pressed member

having a part in the path of and operated 10
by the receptacle while it is being manually
shifted to said position, and means to limit
the pivotal movement of said member, to
limit the movement of the receptacle.

Signed at Newark, N. J., this 11th day of 15
February, 1922.

RAYMOND B. GILCHRIST.
